VINYLACETYLENE PURIFICATION

Charles Keith Buell, Buna Vista, Tex., assignor to
 Phillips Petroleum Company, a corporation of
 Delaware

Application December 9, 1943, Serial No. 513,609

7 Claims. (Cl. 202—42)

This invention relates to a method for recovering vinylacetylene from a complex hydrocarbon mixture containing the same. More specifically, this invention relates to an improved method for recovering vinylacetylene from a complex hydrocarbon mixture containing the same and also containing butenes-2 and any or all of the other aliphatic C₄ acetylenes, diolefins, olefins or paraffins generally encountered in petroleum processes.

Acetylenes appear in small quantities in the reaction products of certain thermal cracking and catalytic dehydrogenation processes. The C₄ acetylenes, namely vinylacetylene, ethylacetylene, bi-acetylene, and dimethylacetylene are of such volatility that they will be concentrated in the C₄ fraction of the reaction product after hydrocarbons of both lower and higher volatility than the C₄ fraction have been removed from said product. The object of my invention is to present a method whereby vinylacetylene may be recovered from a complex hydrocarbon mixture containing the same and also containing butenes-2 and any or all of the other C₄ acetylenes, diolefins, olefins or paraffins generally encountered in petroleum conversion processes.

Vinylacetylene has value as a base for synthetic rubber, drying oils, and resins, and is much in demand at the present time. I have discovered that the recovery of vinylacetylene from a mixed aliphatic C₄ hydrocarbon stream presents a somewhat unusual problem which is very difficult of solution because of the following facts: (1) A relatively small differential exists in the boiling points between butenes-2, vinylacetylene, ethylacetylene and bi-acetylene. (2) A minimum boiling point azeotrope exists between vinylacetylene and butenes-2. (3) A minimum boiling point azeotrope exists between ethylacetylene and butenes-2.

For reference purposes, Table I below shows normal boiling points and normal volatilities of the significant C₄ hydrocarbons.

Table I

Component	Normal boiling point, °Fahrenheit	Normal volatility relative to vinylacetylene ¹
Isobutane	+10.8	1.89
Isobutylene	19.2	1.63
Butene-1	20.7	1.498
1,3 butadiene	23.9	1.43
n-Butane	31.1	1.23
Butene-2 low (cis)	33.6	1.142
Butene-2 high (trans)	38.5	1.034
Vinylacetylene	41.2	1.00
Ethylacetylene	47.8	.895
Bi-acetylene	49.6	.870
Dimethylacetylene	81.0	.423

¹ Normal volatility as here used is defined as the vapor pressure of the particular hydrocarbons at 41.2° F. divided by the vapor pressure of vinylacetylene at 41.2° F. (14.7 pounds per square inch absolute).

I have discovered that the previously mentioned azeotrope between butenes-2 and vinylacetylene is of the minimum boiling point type: that is, the normal boiling point of the azeotrope is lower than that of either butenes-2 or vinylacetylene. My invention takes advantage of this phenomenon by providing for the distillation of the butenes-2 vinylacetylene azeotrope from the other C₄ acetylenes. I have also discovered that various solvents will absorb vinylacetylene in preference to any C₄ diolefins, olefins, or paraffins, and I have utilized this fact to effect a recovery of vinylacetylene from admixture with C₄ diolefins, olefins, and paraffins. One advantage of my invention is that the removal of vinylacetylene from a C₄ system facilitates the purification of certain other individual C₄ hydrocarbons. For example, in certain butadiene purification processes, the final fractionation is made between 1,3 butadiene and butenes-2. If vinylacetylene is present in the system, the formation of the butenes-2 vinylacetylene azeotrope will make the butadiene purification more difficult, because the volatility of the azeotrope is higher than the volatility of butenes-2. Another advantage of my invention is that it makes possible the recovery of vinylacetylene from a C₄ hydrocarbon mixture by the use of conventional petroleum processing equipment, and requires only conventional heating and cooling media. Still another advantage of my invention is that it makes possible the production of acetylene-free C₄ diolefinic, olefinic, and paraffinic hydrocarbons.

The accompanying drawing shows one method for purifying vinylacetylene in accordance with the present invention. A mixed hydrocarbon stream containing butenes-2 and vinylacetylene and comprising any other C₄ acetylenes, diolefins, olefins, or paraffins, is charged via line 4 to the conventional type fractionator 1. The vinylacetylene-butenes-2 azeotrope and most of the C₄ hydrocarbons are removed overhead while substantially all of the other C₄ acetylenes and any C₄ hydrocarbons present are removed as bottom product. However, this separation is possible only if the butenes-2 are present in the fractionator in that quantity required for the formation of the vinylacetylene-butenes-2 azeotrope but not in excess. Since ethyl acetylene and butenes-2 also form an azeotrope of the minimum boiling point type, it is necessary to limit the amount of butenes-2 present to that required to form the more volatile vinylacetylene-butenes-2 azeotrope. Ethylacetylene forms an azeotrope with butene-2 (low boiling) when there is 9.5 per cent ethylacetylene present. Ethylacetylene forms an azeotrope with butene-2 (high boiling) when there is 25.5 per cent ethylacetylene present. Thus the quantity of butenes-2 remaining after all of the vinylacetylene has combined with the butenes-2 to form an

azeotrope must be quite small in order to prevent formation of the ethylacetylene-butenes-2 azeotrope. If too large a quantity of butenes-2 is present it will tend to force the ethylacetylene out the top of the tower thus preventing subsequent recovery of pure vinylacetylene. The overhead product from fractionator 1 is then charged via line 1 to the absorber tower 2 wherein vinylacetylene is removed by selective solvent extraction.

If the feed stream to fractionator 1 does not contain sufficient butenes-2 to allow recovery of all the vinylacetylene in the overhead product, it is necessary to increase the butenes-2 concentration by adding a suitable quantity of butenes-2 continuously to the feed stream or to the fractionation zone. If the feed stream contains too large a percentage of butenes-2 it will be necessary to remove a portion of these butenes-2 in order to prevent formation of an azeotrope between ethylacetylene and the butenes-2. The excess of butenes-2 may be removed by any suitable method.

Among the various selective solvents which will absorb vinylacetylene in preference to C₄ diolefins, olefins and paraffins, are: phenol, phenol plus water, acetone, acetone plus water, dimethylformamide, furfural, furfural plus water, furfuryl alcohol, and methyl levulinate. Any selective solvent which dissolves butadiene in preference to butenes or butenes in preference to butanes should prove satisfactory. For purposes of this discussion, a selective solvent composed of furfural containing a small amount of dissolved water say four weight percent will be used since it is a preferred solvent. Table II shows the relative volatilities at a pressure of 65 pounds per square inch absolute, in this selective solvent, of the C₄ hydrocarbons which may be passed to the absorbing unit.

Table II

Component	Volatility in solvent furfural plus 4 wt. % water, relative to vinylacetylene (at 65 pounds per square inch absolute)
Isobutane.....	4.98
n-Butane.....	3.56
Butene-1.....	2.62
Isobutylene.....	2.46
Butene-2 low.....	1.99
Butene-2 high.....	1.85
Butadiene.....	1.54
Vinylacetylene.....	1.00

The absorber tower 2 is, in effect, a two section extractive distillation tower, the upper section of which acts as an absorber for vinylacetylene while the bottom section of the tower acts as a stripper to remove the other C₄ hydrocarbons which are absorbed to some extent in the top section of the tower. The overhead product from the absorber tower 2, leaving via line 11, is a substantially acetylenes-free stream of C₄ hydrocarbons, and may be further processed for the recovery of individual components if desired. Any C₃ or lighter hydrocarbons retained in the feed to the absorber tower 2 will pass overhead and be removed with the overhead product. Rich solvent leaves absorber tower 2 as the bottoms product, and is charged via line 12 to the solvent stripper 3, wherein vinylacetylene is removed as overhead product while the lean or denuded solvent is returned, after suitable cooling, via line 13 to the top of the absorber tower 2. It may be desirable to carry out the stripping of the vinylacetylene-rich solvent under low pressure (refrigerated)

means, or in the presence of a diluting stripping means in order to reduce hazards and prevent such undesirable reactions as polymerization, etc. Suitable materials for diluting are such inert hydrocarbons as propane, pentane or olefins depending on the ultimate use of the vinylacetylene.

The process of my invention makes readily possible the production of vinylacetylene having a purity of at least 95% or higher up to practically 100%, depending upon the wish of the operator.

The pressure maintained on the fractional distillation column will usually be that required to enable the use of ordinary plant cooling water for condensing the reflux, and therefore will usually be at least about 60 pounds per square inch absolute, varying upward therefrom to say 100 pounds or higher. Use of pressures below 60 pounds is not ordinarily feasible because of excessive refrigeration requirements for condensing the tower reflux. The furfural extractive distillation tower and the stripper operating pressure range will usually be of the same order as that of the fractional distillation tower. In general increase in pressure decreases the selectivity of the solvent for vinylacetylene. Under certain conditions it may be desirable to use refrigeration for condensing the reflux in the extractive distillation tower and stripper tower to prevent the occurrence of undesirable reactions.

The azeotrope between butenes-2 and vinylacetylene boils below butenes-2 but above butadiene. The C₄ hydrocarbons are taken overhead with the vinylacetylene-butenes-2 azeotrope.

In other words, the cut is made at such a point that substantially all of the ethylacetylene and the higher boiling components of the feed appear in the bottoms while virtually all of the isobutane, isobutylene, butadiene, butene-1 and a substantial part of the n-butane go overhead in admixture with the vinylacetylene-butenes-2 azeotrope. There is virtually no butenes-2 taken off from the bottom of the column since it was consumed in the formation of the vinylacetylene-butenes-2 azeotrope. It will be understood that with the complex C₄ mixture usually encountered many unpredictable and complicating factors may affect the theory and result. Thus there is the possibility of the formation of other azeotropes, binary and ternary. For example it is now known that butadiene forms an azeotrope with normal butane. However it has been definitely ascertained that a following of the teachings and principles set out herein will enable the worker in the art to duplicate the results disclosed, namely to separate pure or substantially pure vinylacetylene from any complex aliphatic C₄ hydrocarbon stream containing the same which may be encountered.

Thus my invention depends upon the discovery that by bringing about the formation of the butenes-2 vinylacetylene azeotrope the volatility of vinylacetylene can be so increased from its normal value to a value above that of butenes-2 that essentially complete separation of all the vinylacetylene from the other C₄ acetylenes is assured without necessitating use of special equipment or operations, and further upon the discovery that vinylacetylene can be preferentially dissolved in a selective solvent away from the butenes-2 and the other hydrocarbons in the fractionator overhead which commonly includes butadiene.

While the vinylacetylene-containing C₄ stream treated by the process of my invention will

usually contain other aliphatic C₄ hydrocarbons such as butadiene, butene-1, butenes-2, normal butane, isobutane and isobutylene each in proportions substantially greater than the vinyl-acetylene, my invention is not limited to such a stream but is applicable to streams containing a much larger relative proportion of vinylacetylene and less or practically no butadiene, butene-1, butenes-2, normal butane, isobutane, or isobutylene.

From the foregoing, it will be seen that the present invention is based upon the discovery that minimum-boiling azeotropes are formed not only between vinylacetylene and butenes-2 but also between the other C₄ acetylenes and butenes-2. Furthermore, it will be seen that the present invention accomplishes the removal of vinylacetylene substantially uncontaminated with other C₄ acetylenes by providing in the fractionation zone an amount of butenes-2 sufficient to form minimum-boiling azeotropes with all of the vinyl-acetylene present in the feed but not in a substantial excess of this amount. By operating in accordance with the present invention, any other C₄ acetylenes go out the bottom while the vinylacetylene is selectively taken overhead in the form of its azeotropes with butenes-2. If desired, the feed stream may be preliminarily given a solvent extraction to concentrate the C₄ acetylenes where the butenes-2 are present in too great a quantity. Then the correct amount of butenes-2 based on the vinyl-acetylene content would be added to the butenes-2 free stream thus obtained and the resulting mixture would be passed to tower 1.

It is to be understood that the foregoing illustrative disclosure is not limiting and that the invention is to be taken as limited only by the terms and spirit of the appended claims.

I claim:

1. The process of recovering vinylacetylene in concentrated form from a C₄ hydrocarbon stream containing the same and other aliphatic C₄ hydrocarbons which comprises fractionally distilling said stream while maintaining in the fractionation zone butenes-2 in sufficient amount to form a minimum boiling point azeotrope with vinyl-acetylene and virtually no excess butenes-2, recovering overhead this azeotrope between said vinylacetylene and said butenes-2, subjecting the overhead fraction to selective solvent extraction and thereby selectively dissolving the vinylacetylene in the selective solvent, and stripping the rich solvent to recover concentrated vinylacetylene as the product of the process.

2. The process of recovering vinylacetylene in concentrated form from a C₄ hydrocarbon stream containing the same and other more saturated C₄ hydrocarbons including isobutane, isobutylene,

butadiene, butene-1, normal butane and butenes-2, at least one of said other more saturated C₄ hydrocarbons being present in quantity substantially greater than the proportion of vinyl-acetylene, and also containing substantial proportions of other C₄ acetylenes which comprises fractionally distilling said stream in the presence of butenes-2 in amount just sufficient to form a minimum boiling point azeotrope with the vinyl-acetylene present, recovering an overhead consisting of an azeotrope of said butenes-2, and said vinylacetylene in admixture with a substantial proportion of said other more saturated C₄ hydrocarbons, subjecting the overhead fraction to extractive distillation in the presence of a solvent selective for vinylacetylene in preference to more saturated C₄ hydrocarbons and thereby selectively dissolving the vinylacetylene in the selective solvent while allowing said other more saturated C₄ hydrocarbons to pass through undissolved, and stripping the rich solvent to recover concentrated vinylacetylene as the product of the process.

3. The process of recovering vinylacetylene in concentrated form from a C₄ hydrocarbon stream containing the same and other more saturated C₄ hydrocarbons including isobutane, isobutylene, butadiene, butene-1, normal butane and butenes-2, at least one of said other more saturated C₄ hydrocarbons being present in quantity substantially greater than the amount of vinylacetylene, and also containing a substantial proportion of at least one other C₄ acetylene which comprises fractionally distilling said stream in the presence of butenes-2 in amount just sufficient to form a minimum boiling azeotrope with the vinylacetylene present, recovering an overhead consisting of an azeotrope of said butenes-2 and said vinylacetylene in admixture with a substantial proportion of said other more saturated C₄ hydrocarbons including substantially all of said butadiene and butene-1, subjecting the overhead fraction to extractive distillation in the presence of a solvent selective for vinylacetylene in preference to more saturated C₄ hydrocarbons and thereby selectively dissolving the vinylacetylene in the selective solvent while allowing said other more saturated C₄ hydrocarbons to pass through undissolved, and stripping the rich solvent to recover concentrated vinylacetylene as the product of the process.

4. The process of claim 1 wherein said solvent is furfural.
 5. The process of claim 1 wherein said solvent is furfural plus 4 weight per cent of water.
 6. The process of claim 2 wherein said solvent is furfural.
 7. The process of claim 3 wherein said solvent is furfural.

CHARLES KEITH BUELL.
